Attorney*

UNITED STATES PATENT OFFICE.

GASTON JULES DALOZ, OF COURBEVOIE, FRANCE.

COMPRESSOR.

1,394,811.

Specification of Letters Patent. Patented Oct. 25, 1921.

Application filed December 27, 1919. Serial No. 347,851.

To all whom it may concern:

Be it known that I, GASTON JULES DALOZ, a citizen of the French Republic, residing at No. 20 Avenue Galliéni, Courbevoie, Seine, France, have invented certain new and useful Improvements in Compressors, for which I have filed an application in Germany, April 1, 1914, of which the following is a specification.

This invention has for its object to provide an improved compressor of the known type wherein the cylinders are arranged parallelly to one another at different points of a circle, and the heads of the piston connecting rods are pivoted on a cap which is mounted by means of a Cardan joint on the compressor frame, and is provided with a pin driven from an eccentric point of a disk revolving at right angles to the axis of the compressor.

The improved compressor is characterized by the combination of the hereinafter described detail features which facilitate its construction and taking apart, and improve 25 its working.

A constructional form of the improved compressor will now be more particularly described, designed to be mounted upon a vehicle (railroad car or tramcar) and for this 30 purpose it is mounted together with its driving motor in a cradle which is arranged transversely or longitudinally of the axis of the car and is fixed by its ends on the longitudinal or cross members of the car. The

35 compressor is driven by an electric motor likewise mounted on the cradle. The air to be compressed is drawn in through the motor casing which is made tight so that this arrangement has the advantage of cooling the 40 electric motor by ventilation. These features are likewise part of the invention. The motor-compressor group thus constituted has a very small weight and bulk for a given power and can be mounted very easily 45 upon the chassis of the vehicle.

In the accompanying drawings:

Figure 1 is a section of the improved compressor, and

Fig. 2 is a side elevation of the motor-compressor group partly in section. 50

As shown, the cradle 1 ending in fixing lugs 2 and 3 carries on the left an electric motor 4 and on the right the improved compressor.

The improved compressor is constructed 55 as follows:

Its lower part comprises a casing 5 containing the power-transmitting and receiving mechanism. The upper part of the casing carries a set of cylinders 6 arranged in a 60 circle. The cylinders of the set are connected together at their upper ends by a cylindrical collector 49 formed with the apertures for the valves, and they are connected together at their lower part by an annular 65 base 34, and they are further connected at mid length by an annular assembling flange 38 to the said casing.

The casing 7 of the electric motor and the casing 5 are assembled together in such a 70 manner as to form a single bearing composed of two parts 8 and 9 supporting by means of a set of bearing balls 10, the motor shaft 11 which drives through an Oldham joint the spindle 12 of a worm 13 whose end 75 14 is journaled in a thrust bearing 15 in the motor casing. The worm 13 meshes with a horizontal worm wheel 16 supported by a vertical journal 17 working in a footstep bearing 18 formed on the under side of the 80 casing 5. The worm wheel 16 has a boss containing a ball bearing 19.

To the lower annular base 34 of the set of cylinders there is bolted a bracket 20 serving to carry one of the axles 21 of a Cardan 85 joint, of which the other axle at right angles carries a cap 22 extended downwardly by a pin 23 whose end is engaged in the inner ring of the ball bearing 19. Inside the chamber 24 of each cylinder there works a 90 piston 25 connected to a connecting rod 26. This connecting rod terminates at its upper end in a ball 27 fixed in a central boss 28 of the piston by being clamped between a lower bearing step 29 which is suitably recessed, located in the bottom of the cavity of the

said boss, and an upper bearing step 30 screwed above the ball 27 in the said cavity of said boss. At its lower part the connecting rod 26 terminates likewise in a ball 31 fixed in a cavity of the cap 22 by means of a lower bearing step 32 engaged in the bottom of the said cavity, and an upper bearing step 33 pierced with a suitable aperture for the passage of the connecting rod and 10 screwed in the cavity of the cap 22 so as to imprison the ball 31.

The cylinder block 6 rests by means of its bottom rim 34 upon a seat 35 of the lower casing 5. This lower casing 5 extends up 15 beyond the seat 35 in the form of a cylindrical wall 36 terminating in a flange 37 fitting against a flange 38 provided at a suitable height on the cylinder block 6. The two flanges 37, 38 are connected together by 20 nutted bolts 39. By this arrangement, an annular space 40 is provided between the lower casing and the upper casing. The suction of the cylinders takes place through holes 41 opening into the space 40 comprised 25 between the lower casing and the cylinder block. These holes are situated at such a height that they will be uncovered by the pistons 25 when the latter are at the bottom of their stroke as shown in the right hand 30 cylinder, and that they will not be uncovered when the pistons are at the top of their stroke as shown in the left hand cylinder.

The suction of the compressor draws from the annular chamber 40, and this has the advantage of doing away with the noise caused by this suction. While at the same time any dust that has been carried in by the air will settle in this annular chamber and will not pass into the cylinders with the indrawn 40 air. Since the suction holes 41 are not uncovered by the piston at the top of its stroke, the lubricating oil contained in the lower casing 5 and upon the moving parts, cannot be thrown out through these holes 45 into the chamber 40, and thereby be drawn into the cylinders with the indrawn air.

In the motor-compressor group shown in the drawings, the suction takes place also through the completely air-tight casing of 50 the electric motor 4, thus serving to cool the latter. This suction takes place through a tube 42 situated at the side of the collector, provided with a cap 43 arranged with perforated plates 44 and a metal filter 45 serving 55 to arrest the dust. After the indrawn air has flowed between the motor and its casing, it passes into a pipe 46 connected to the suction chamber 40 after having passed through a metal filter 47 for arresting the 60 dust, chiefly the dust which may have got through the collector 48 if the latter has become worn or faulty.

The upper part 6 of the compressor casing constitutes a delivery chamber 49 provided with a delivery pipe 50 into the lower

part of which the delivery valves 51 open. Each of these valves has a stem 52 guided in a part 53 fixed to the upper part of the delivery chamber 49. This guiding part 53 is held in place by a sleeve 54 which is itself 70 held in position by a cap 55 screwed on the upper part of the delivery chamber 49. The valve 51 is kept pressed against its seat by a spring 56 bearing upon a cup washer 57 mounted on the upper end of the stem 52. 75 A stud 58 screwed into the cap 55 and fastened by a lock nut 59, serves as an adjustable stop for the end of the valve stem 52. Owing to this arrangement, the spring 56 is situated in a chamber into which the compressed gases do not enter, and the said spring is therefore protected from the destructive action of these hot gases. 80

In order to allow of regulating the piston stroke and consequently the dead spaces at 85 the bottom of the cylinders, the outer ring 60 of the ball bearing 19, carried by the worm wheel 16, has an outer surface which is eccentric relatively to its inner surface. It is screwed in this cavity in such a manner 90 that by screwing it more or less in or out, the inner ring of the ball bearing 19 can be moved farther away from or nearer to the center of the wheel 16, thereby increasing or diminishing the amplitude of the conical 95 rocking movement of the pin 23 of the cap, with the result of increasing or diminishing the piston stroke.

What I claim is:—

1. A device of the type described comprising an annular group of cylinders, pistons reciprocally mounted therein, a cap member mounted for universal movement, a member rotatable in a plane perpendicular to the axis of the cylinder, means connecting said rotatable member with said cap member whereby rocking movement is imparted to the latter to effect reciprocation of said pistons, and means for adjusting the last mentioned means to vary the extent of the rocking movement of the cap member.

2. A device of the type described comprising an annular group of cylinders, pistons reciprocally mounted therein, a cap member mounted for universal movement, means connecting said cap member with said piston, a member rotatable in a plane perpendicular to the axis of the cylinders, means connecting the rotatable member and the cap member whereby rocking movement of the cap member is produced incident to rotation of the rotatable member, and means for varying the position of the connecting means with respect to the axis of the rotatable member for varying the extent of rocking 125 movement of the cap member.

3. A device of the type described comprising an annular group of cylinders, pistons reciprocally mounted therein, a cap member mounted for universal movement, means 130

connecting said cap member with said pistons, a member rotatable in a plane perpendicular to the axis of the cylinders, a pin carried by the rotatable member and engaged
5 with the cap member for effecting rocking movement of the latter incident to rotation of the rotatable member, and an adjustable mounting for said pin for varying the posi-

tion of the latter with respect to the axis of the rotatable member whereby the extent 10 of the rocking movement of the cap member may be varied.

In testimony whereof I have signed my name to this specification.

GASTON JULES DALOZ.
